Patented June 2, 1970

217,719

STEAM GENERATOR FOR COMPLEXION CARE

Samuel L. McNair, Overland Park, Kans., and Thomas W. Kellogg, Newport Beach, Calif., assignors to The Songrand Corporation, a corporation of Missouri

Filed Feb. 19, 1969, Ser. No. 15,837

Term of patent 14 years

Int. Cl. D23—04

U.S. Cl. D23—148

FIG. 1 is a front perspective view of a steam generator for complexion care showing our new design;

FIG. 2 is an enlarged side elevational view of the steam generator as seen from the left hand side of FIG. 1, the other side being a mirror image thereof;

FIG. 3 is a rear elevational view of same; and

FIG. 4 is a top plan view of same.

We claim:

The ornamental design for a steam generator for complexion care, as shown and described.
